Term of patent 14 year

(Cl. D44—9)

FIG. 1

FIG. 2

FIG. 3

FIG. 4

FIG. 5

FIG. 6

FIG. 7

FIG. 1 is a top perspective view of a cup showing my design;

FIG. 2 is a front elevational view;

FIG. 3 is a side elevational view;

FIG. 4 is a rear elevational view;

FIG. 5 is a top plan view;

FIG. 6 is a bottom plan view; and

FIG. 7 is a cross sectional view taken approximately along line 7—7 of FIG. 5 and looking in the direction of the arrows.

The dominant feature of this design resides in the vertical parallel handle receiving sockets in combination with a handle having vertical parallel legs, the lower ends of which are inserted in said sockets, the upper ends of which are joined by an inwardly extending arcuate bight

portion contiguous with the outer wall of the cup body.

I claim:

The ornamental design for a cup, as shown and described.
